AUTOMATIC REEL

Walter E. Nordmark, Grand Rapids, Mich., assignor to American Seating Company, Grand Rapids, Mich., a corporation of New Jersey

Application October 2, 1946, Serial No. 700,673

12 Claims. (Cl. 242—107)

1

The present invention relates to automatic reels, and more particularly to an automatic, inertia-operated, safety reel for taking up the cable of a shoulder harness by means of which an occupant of an airplane or other vehicle is secured in his chair.

The primary objects of the invention are to provide an improvement of the automatic reel disclosed in my copending application Serial #587,411, filed April 9, 1945; to provide a reel for reeling in and paying out the cable of a shoulder harness to permit freedom of movement to the wearer of the harness, which reel has inertia-actuated parts for preventing paying out of the cable during a collision or crash landing and which has means for positively locking the reel during such emergency and maintaining the same in locked condition until such emergency has passed and the reel is manually unlocked.

These objects are attained by the illustrative embodiment of the invention shown in the accompanying drawings, wherein:

Figure 1 is a perspective view, from the side and rear, of an automatic inertia-operated cable reel showing my new locking device incorporated therein;

Figure 2 is a rear elevational view of the device, the housing member thereof being shown in vertical section taken on line 2—2 of Figure 3;

Figure 3 is an enlarged sectional view thereof taken on line 3—3 of Figure 2;

Figure 4 is a view partly in top plan and partly in section similar to Figure 3 and showing certain parts of the device in different moved positions;

Figure 5 is a view similar to Figure 4 and showing parts of the device in still other moved position.

The automatic reel shown in these drawings is adapted to be secured to the rear panel 10 (shown fragmentarily in Figures 3—5) of a vehicle chair such as the pilot seat of an airplane as by means of bolts 11 and nuts 12, and is adapted for attachment to a shoulder-harness (not shown) for the chair occupant in such manner that the cable is payed out when the occupant leans forwardly in the chair and is taken up by the reel when the occupant leans rearwardly. The normal sitting position is, of course, with the back of the occupant against the chair back in which position a maximum amount of the cable is taken up by the reel. However irrespective of the occupant's position, it is desirable that the reel lock against paying out at the time of collision or crash-landing of the vehicle so that the chair occupant

2

is secured against being thrown farther forward and thus possibly injured by contact with the instrument panel, controls, or other part of the vehicle. The probability is that the chair occupant will be in a normal sitting position against the chair back at the time of such emergency, and it is therefore desirable that the cable reel be positively locked against paying out after an initial crash until such time that the reel is manually unlocked, thus to prevent injury to the occupant during ensuing crashes or rebounds. The mechanism for temporarily locking the reel at the instant of a crash is described in detail and claimed in my co-pending application identified above, and it is briefly described below in order to make clear the relationship between said mechanism and the "stay-lock" mechanism of the present invention.

The bolts 11 and nuts 12, in addition to securing the automatic reel to the rear panel 10 of the chair back, serve also to secure the base 14 and the housing member 15 of the device together in assembly. The base 14 has a central, rearwardly extending spindle 16 provided with a forward flange 17 secured in a recess 18 in the base by means of rivets 19. A machine screw 20 threaded in the rearward end of the spindle 16 secures the center of the housing member 15 to the spindle.

A drum 21 is rotatably and slidably mounted on the spindle 16, and the cable 13 has one end thereof secured to the drum and extends through an opening in the housing member 15, the other end of said cable being secured to the shoulder harness. A coil spring 22 has one end thereof secured to the spindle 16 and the other end thereof secured to the drum 21 and said spring 22 normally urges the drum 21 in a direction for winding the cable 13 thereon, thus to take up any slack in the cable. The cable is wound into a recess 23 in the drum 21. The base 14 and drum 21 are provided with complementary interlocking ratchet surfaces 24 and 25 respectively which are adapted to engage when the drum slides forwardly toward the base to prevent rotation of the drum in a direction for unwinding and paying out the cable 13. A spring unit comprising complementary leaf springs 26 and 27 is interposed between the base 14 and drum 21 so that the drum 21 is normally urged away from the base and the ratchet surfaces 24 and 25 are thus normally disengaged to permit paying out of the cable in response to the chair occupant's forward movements. In the event of a collision or other emergency as above described, the inertia of the

drum 21 causes the drum to slide forwardly relative to the vehicle and into ratchet engagement with the base 14 thus to prevent paying out of the cable at such time.

The chair occupant may under certain conditions prefer to set the device so that the drum is in ratchet engagement with the base and the cable 13 is thus prevented from paying out. This may be accomplished by means of a manually controlled switch (not shown) located within reach of the chair occupant and connected by a flexible control cable 28 to a control lever 29 fulcrumed in the housing member 15 and provided with a yoke arm 30 adapted to bear against opposite sides of the rearward surface of the drum 21. The yoke arm 30 is normally urged rearwardly by means of a coiled compression spring 31 interposed between the head 32 of a pin 33 on the control cable 28 and a bracket 34 secured to the housing member 15 and having therein a slide bearing for the pin 33. A tension spring 35 provides a yielding connection between the pin 33 and the control lever 29, so that when the drum is moved forwardly by means of the yoke arm, said drum is free to rotate in a direction for taking up cable slack, but not to rotate in the opposite or paying-out direction.

The "stay-lock" or permanent locking mechanism of the present invention comprises a spring metal leaf 36 having an end 37 thereof secured as by rivets 38, 39 to the housing member 15, said housing member thus serving as a mounting member for mounting the end 37 of the leaf spring 36 in fixed relation to the base 14 of the device. A locking pin 40 is secured near the other end 41 of the spring leaf 36 and extends through an opening 42 in the housing member 15, transaxially of the drum. The spring metal leaf 36 normally urges the locking pin 40 into engagement with the outer peripheral surface of the drum 21, rearwardly of the cable-receiving recess 23 in the drum, and the pin 40 thus bears against the rotating drum when the drum is in its normal, rearward position shown in Figure 3. It will be seen, however, that when the drum 21 is slid forwardly by inertia into ratchet engagement with the base 14 as shown in solid lines in Figure 4, the spring leaf 36 urges the locking pin 40 inwardly and behind the drum 21. When the pin is in this position, the drum is positively prevented from moving rearwardly beyond its position of engagement with the pin 40 and with the base 14, as seen in dotted lines in Figure 4. The drum is thus locked against rotation in either direction and the cable is neither taken up nor payed out when this condition obtains.

In order that the reel may be manually unlocked after the emergency has passed, the free end 41 of the spring metal leaf 36 is extended upwardly into engagement with the control lever 29. It will be seen that manual movement of the control lever 29 to its solid line position shown in Figure 5, will also move the spring leaf 36 to its position shown in solid lines in this view, thus withdrawing the locking pin 40 from the path of the drum's sliding movement. When the control lever is released and the drum is urged rearwardly by the spring unit 26, 27, said drum enters the path of inward movement of the locking pin as indicated in dotted lines in Figure 5, and the drum and locking pin ultimately assume their original, normal positions shown in Figure 3.

It will thus be seen that the present invention provides a "stay-lock" feature for a cable reel

of the temporary inertia-locking type, and while but one specific embodiment of the invention has been herein shown and described it will be understood that other embodiments thereof may fall within the scope of the following claims without departing from the spirit of the invention.

I claim:

1. In a device of the class described, a base, a drum slidably mounted on the base and rotatable thereon, interlocking means on the base and the drum adapted to engage when the drum is slid toward the base, locking means operable by the sliding movement of the drum toward the base for automatically locking said drum in its slid position of interlocking engagement with the base, and manually operable means for releasing said locking means.
2. In a device of the class described, a base, a drum slidably mounted on the base and normally rotatable in both directions thereon, interlocking means on the base and the drum adapted to engage when the drum is slid toward the base to prevent rotation of the drum in one direction, locking means operable by the sliding movement of the drum toward the base for automatically locking said drum in its slid position of interlocking engagement with the base, and manually operable means for releasing said locking means.
3. In a device of the class described, a base, a drum slidably mounted on the base and rotatable thereon, interlocking means on the base and the drum adapted to engage when the drum is slid toward the base, means for normally urging the drum away from the base, locking means operable by the sliding movement of the drum toward the base for automatically locking said drum in its slid position of interlocking engagement with the base, and manually operable means for releasing said locking means.
4. In a device of the class described, a base, a drum rotatably and slidably mounted on the base, a cable connected to said drum and adapted to be wound thereon, means for normally yieldingly urging said drum in a rotating direction for winding the cable thereon, interlocking means on the base and the drum adapted to engage when the drum is slid in one direction relative to the base to thus prevent rotation of the drum in a direction for unwinding the cable, locking means operable by the sliding movement of the drum in said one direction for automatically locking the drum in said slid position, and manually operable means for releasing said locking means.
5. In a device of the class described, a base, a drum rotatably mounted on the base and slidable relative thereto, means for normally yieldingly urging the drum away from the base, a cable connected to said drum and adapted to be wound thereon, means for normally yieldingly urging said drum in a rotating direction for winding the cable thereon, interlocking means on the base and the drum adapted to engage when the drum is slid toward the base to thus prevent rotation of the drum in a direction for unwinding the cable, locking means operable by the sliding movement of the drum toward the base for automatically locking the drum in its slid position of interlocking engagement with the base, and manually operable means for releasing said locking means.
6. In a device of the class described, a base, a drum slidably mounted on the base and rotatable thereon, interlocking means on the base and the drum adapted to engage when the drum is slid

toward the base, a mounting member associated with the base, a locking pin mounted on the mounting member movable transaxially of the drum, a spring on the mounting member for urging the locking pin into normal engagement with the outer periphery of the drum and into automatic locking engagement behind said drum when the drum is slid into interlocking engagement with the base.

7. In a device of the class described, a base, a drum slidably mounted on the base and rotatable thereon, interlocking means on the base and the drum adapted to engage when the drum is slid toward the base, a mounting member associated with the base, a locking pin mounted on the mounting member movable transaxially of the drum, a spring on the mounting member for urging the locking pin into normal engagement with the outer periphery of the drum and into automatic locking engagement behind said drum when the drum is slid into interlocking engagement with the base, and manually operable means for releasing said locking means.

8. In a device of the class described, a base, a drum slidably mounted on the base and normally rotatable in both directions thereon, interlocking means on the base and the drum adapted to engage when the drum is slid toward the base to prevent rotation of the drum in one direction, a mounting member associated with the base, a locking pin mounted on the mounting member movable transaxially of the drum, and a spring on the mounting member for urging the locking pin into normal engagement with the outer periphery of the drum and into automatic locking engagement behind said drum when the drum is slid into interlocking engagement with the base.

9. In a device of the class described, a base, a drum slidably mounted on the base and rotatable thereon, interlocking means on the base and the drum adapted to engage when the drum is slid toward the base, means for normally urging the drum away from the base, a mounting member associated with the base, a locking pin mounted on the mounting member movable transaxially of the drum, a spring on the mounting member for urging the locking pin into normal engagement with the outer periphery of the drum and into automatic locking engagement behind said drum when the drum is slid into interlocking engagement with the base, and manually operable means for releasing said locking means.

10. In a device of the class described, a base, a drum rotatably and slidably mounted on the base, a cable connected to said drum and adapted to be wound thereon, means for normally yieldingly urging said drum in a rotating direction for winding the cable thereon, interlocking means on the

base and the drum adapted to engage when the drum is slid in one direction relative to the base to thus prevent rotation of the drum in a direction for unwinding the cable, a mounting member associated with the base, a locking pin mounted on the mounting member movable transaxially of the drum, and a spring on the mounting member for urging the locking pin into normal engagement with the outer periphery of the drum and into automatic locking engagement behind said drum when the drum is slid into interlocking engagement with the base.

11. In a device of the class described, a base, a drum rotatably mounted on the base and slidably relative thereto, means for normally yieldingly urging the drum away from the base, a cable connected to said drum and adapted to be wound thereon, means for normally yieldingly urging said drum in a rotating direction for winding the cable thereon, interlocking means on the base and the drum adapted to engage when the drum is slid toward the base to thus prevent rotation of the drum in a direction for unwinding the cable, a mounting member associated with the base, a locking pin mounted on the mounting member movable transaxially of the drum, a spring on the mounting member for urging the locking pin into normal engagement with the outer periphery of the drum and into automatic locking engagement behind said drum when the drum is slid into interlocking engagement with the base, and manually operable means for releasing said locking means.

12. In a device of the class described, a base, a drum slidably mounted on the base and normally rotatable in both directions thereon, means for normally yieldingly urging the drum away from the base, a cable connected to said drum and adapted to be wound thereon, means for normally yieldingly urging said drum in a rotating direction for winding the cable thereon, interlocking ratchets on the base and the drum adapted to engage when the drum is slid toward the base to thus prevent rotation of the drum in a direction for unwinding the cable, a housing member mounted on the base and enclosing said drum, a leaf spring secured to the exterior of said housing member, a locking pin secured to the leaf spring and extending through an aperture in the housing member and bearing against the outer periphery of said drum, said locking pin being pressed by the leaf spring into normal engagement with the outer periphery of the drum and into automatic locking engagement behind said drum when the drum is slid into ratchet interlocking engagement with the base, and manually operable means for releasing said locking means.

WALTER E. NORDMARK.
